UNITED STATES PATENT OFFICE.

JOHN H. CILLEY, OF LEBANON, PENNSYLVANIA.

TRICYCLE.

SPECIFICATION forming part of Letters Patent No. 328,761, dated October 20, 1885.

Application filed September 10, 1885. Serial No. 176,684. (No model.)

To all whom it may concern:

Be it known that I, J. H. CILLEY, a citizen of the United States, residing at Lebanon, in the county of Lebanon and State of Pennsylvania, have invented certain new and useful Improvements in Tricycles; and I do hereby declare the following to be a full, clear, and exact description of the invention, such as will enable others skilled in the art to

10 which it appertains to make and use the same.

My invention relates to an attachment for tricycles, whereby the ordinary tricycle of the "front-steering" class may be converted into a tandem velocipede to carry two riders.

15 The attachment consists of a frame, which, in the present instance, to illustrate my invention, is an exact counterpart of that which projects forward from the axle of the "Columbia tricycle," and is provided with a 20 wheel, pedal-crank axle, saddle, and handle-bars. The frame is provided with side bars, having on their ends clips for attaching it to the axle of the tricycle and for forming a vertical joint to allow the frame to rise and fall 25 to compensate for any irregularities in the road.

In the accompanying drawings, which form a part of this specification, Figure 1 represents a side view of a Columbia tricycle provided with my attachment; Fig. 2, a rear view of the same; Fig. 3, a side view of the attachment detached from the tricycle; Fig. 4, a side view of the spring-clip and a section of the ball-bearing case on the axle; Fig. 5, a top 35 view of the same; and Figs. 6 and 7 represent details of the construction of the steering-rod and its slide-bearing.

Reference being had to the drawings and the letters of reference marked thereon, A represents the frame of a tricycle to which the attachment is connected. The construction of this part of the machine being well known it will require only a general description of such parts as are necessary to understand my invention. a is the axle, upon which are mounted the driving-wheels b b; c, the small steering-wheel; d, the seat; e, the pedal-crank axle; f, the steering-handle; g, the driving-gear.

B represents the attachment for forming the tandem velocipede. a' a' are the side bars of the frame, upon the ends of which are formed

spring-clips b' b', which, in the present instance, are adapted to fit over and engage with the ball-bearing case c' of the main axle a. d' is the swinging-latch of the clip, connected to 55 the frames a' a' at e', and adapted when thrown into contact with the spring-clip to engage therewith by the former passing through the slot f, formed in the latch, as shown in Figs. 3, 4, and 5.

The frame or attachment is provided with a wheel, C, a pedal-crank axle, D, a saddle, E, and handles F F, which correspond with those on the main machine. The seat or saddle E is adjustably supported upon an arched 65 portion, G, rising vertically from the side bars, a' a', of the frame. The arch or seat-support is braced to the rear portion of the frame, as shown at i i.

A foot-rest, H, is secured between the forward ends of the side bars for the accommodation of the rear rider when not operating the pedal-crank axle of the attachment. The frame of the attachment is of the same length and width as the main frame, and the front 75 and rear wheels are therefore equidistant from the main axle. By this construction the machine is perfectly balanced and causes it to run evenly and smoothly without the jar which is incident to the single machine. The 80 front and rear frames being of the same width the machine becomes a "three-track machine," as the rear wheel follows in the same track as the front wheel.

Upon the main axle is permanently attached 85 an additional driving or sprocket wheel, I, over which is passed a chain having a removable bolt (not shown) connecting the links at one point to provide for its being separated to attach it to the wheel I on the main axle 90 and the wheel J on the pedal-crank axle D of the auxiliary frame.

The machine is steered wholly by the front rider; and to this end the front and rear wheels are connected by a rod, K K, which is attached to a lug, k, on the rod l, leading from the arm m of the front wheel to the steering-handle f. To the inside of the main frame and the safety-stay is secured a guideway, n, in which is placed a slide, o, from which projects 95 a stud or pin, p, upon which the inner ends of the rods are secured by a suitable washer,

thus forming a joint in the rod K K, which accommodates itself to any irregularities in the road, such as deep gutters or gullies, in crossing which the front and rear parts of the machine are thrown out of the same horizontal plane. By connecting the front and rear wheels they are always under the control of the front rider, and are made to trail very accurately by reason of the rear wheel, C, having its steering arm or lever *q* project from the opposite side of the wheel as compared with the wheel *c* and its arm *m*, and that they are equidistant from the main axle, thus enabling the machine to be turned in a very small space.

Upon reference to Figs. 4 and 5, it will be observed that the side bars, *a' a'*, of the frame are flattened at their ends and slightly bent, to facilitate the connection with the ball-bearing case, and that by connecting the frame to the said case no additional friction is incurred.

Another advantage of my construction is that the tension of the rear driving-chain is not affected by any of the irregularities in the road, as the vertical joint formed by attaching the rear frame to the ball-bearing case on the main axle allows the entire frame to swing freely without in any manner changing the tension of the drive-chain connecting the rear pedal-crank axle with the main axle.

The front and rear frames being connected together by their attachment to the main axle in the same vertical plane form a very stiff and substantial machine, and in climbing hills are found to balance each other perfectly, thus enabling both riders to work on their respective pedal-crank axles without danger of tilting either end.

The crank-axles are set at different angles, as shown in Figs. 1 and 2, thus always providing against the machine being upon a dead-center, or one rider working against the other, and presenting a ready means for starting the machine from any position in which it may have been stopped.

I would have it understood that my invention is not limited in its application to the style of tricycle to which it is shown attached; but that it is susceptible of changes to adapt it to different styles, which are mere mechanical expedients, and are held to be within the spirit and scope of my invention.

I am aware that tricycles have heretofore

been provided with parts for converting them into tandem velocipedes, and do not, therefore, claim such an attachment, broadly; but,

Having fully described my invention, what I claim is—

1. An attachment for tricycles, consisting of a frame provided with continuous side bars having their ends formed into clips for attaching them to the main axle, substantially as set forth.

2. An attachment for tricycles, consisting of an auxiliary frame provided with side bars having clips formed on their ends, in combination with the ball-bearing cases on the main axle, substantially as described.

3. An attachment for tricycles, consisting of an auxiliary frame provided with side bars having their ends reduced and formed into spring-clips, substantially as described.

4. An attachment for tricycles, consisting of an auxiliary frame having side bars and an arched seat-support connecting said bars, substantially as described.

5. An attachment for tricycles, consisting of an auxiliary frame having side bars, an arched seat-support connecting said bars, and a foot-rest, substantially as described.

6. A velocipede having a fixed and a swinging frame, two driving-wheels, a front and rear steering-wheel, and a suitable steering device connecting said steering-wheels, substantially as described.

7. A velocipede having a front frame fixed to the axle and a rear frame detachably secured thereto provided with steering-wheels, in combination with a rod attached to both steering-wheels and connected to a slide in a guideway attached to the frame, substantially as described.

8. A velocipede having a swinging frame attached to the main axle, two driving-wheels, front and rear steering wheels, in combination with a rod connecting said wheels provided with a joint to admit of vertical movement of the rod and swinging frame, substantially as and for the purpose set forth.

In testimony whereof I affix my signature in presence of two witnesses.

JOHN H. CILLEY.
